(57) **CLAIM**

I claim the ornamental design for a wire-wrapped heart-shaped pendant, as shown and described.

DESCRIPTION

FIG. 1 is a top front isometric view of a wire-wrapped heart-shaped pendant showing my new design;

FIG. 2 is a top rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depicting a necklace illustrate environmental structure. All other broken lines illustrate portions of the wire-wrapped heart-shaped pendant. The broken lines form no part of the claimed design.
